PASSENGER VESSEL

Luther H. Blount, Bristol, R.I., assignor to Blount Marine Corporation, Warren, R.I., a corporation of Rhode Island

Filed Apr. 1, 1969, Ser. No. 16,544

Term of patent 14 years

Int. Cl. D12—06

U.S. Cl. D71—1

Fig. 1.

Fig. 2.

Fig. 3.

FIG. 1 is a top plan view of a passenger vessel embodying my new design;

FIG. 2 is a side elevation thereof; the opposite side being a mirror image thereof; and

FIG. 3 is a front or bow view thereof, with the mast being omitted for convenience of illustration.

I claim:

The ornamental design for a passenger vessel, substantially as shown and described.
